UNITED STATES PATENT OFFICE.

HUBERT L. JUDD, OF BROOKLYN, NEW YORK.

DESIGN FOR A TASSEL-HOOK.

Specification forming part of Design No. 5,480, dated January 23, 1872.

To all whom it may concern:

Be it known that I, HUBERT L. JUDD, of Brooklyn, in the county of Kings and State of New York, have invented or produced a Design for a Tassel-Hook; and the following is declared to be a full and correct description of the same:

This design relates to the shape or configuration of the tassel-hook, and to the ornamentation upon the same. The tassel-hook is made in two parts, a back plate to be secured to the wall or other place of attachment, and a front plate at the end of an arm extending from the back plate.

In the drawing, Figure 1 is an elevation of the tassel-hook complete. Fig. 2 is an elevation of the back plate; and Fig. 3 is a vertical section of said tassel-hook.

The general outline of the back plate *a* is that of diamond, with the bevelled edges *b*, ornamented by the "Grecian" border *c*, except at the angles, where the border is made with concave sunken panels *d*, of the shape shown. Scroll-ornaments are shown at *e e*, and at *ff*

screw-holes are provided, surrounded partly by scroll-ornaments. The surfaces of the recessed panels are of "stipple" work, and leaf-ornaments are introduced in the central panel of the plate *a*, as seen in Fig. 2, at *h*. The hook or front plate *m* at the central portion is ornamented by the medallion *n*, in relief, partially surrounded by the milled edge and scalloped border *p*. The upper and lower portions of the hook are formed with leaf-and-scroll ornaments in relief upon the sunken surface, as shown.

I claim as my invention—

1. The back-plate *a*, of the shape or configuration shown, and ornamented substantially as described and represented.

2. The front plate or hook, of the shape or configuration shown, and ornamented substantially as described and represented.

Signed by me this 29th day of December, A. D. 1871.

Witnesses: HUBERT L. JUDD.
